UNITED STATES PATENT OFFICE

JOSEPH SCHRADER, OF CLEVELAND, OHIO

DESIGN FOR A LAMP

Application filed January 20, 1933. Serial No. 46,908. Term of patent 3½ years.

To all whom it may concern:

Be it known that I, JOSEPH SCHRADER, a citizen of the United States, residing at Cleveland, in the county of Cuyahoga and State of Ohio, have invented a new, original, and ornamental Design for a Lamp, of which the following is a specification, reference being had to the accompanying drawing, forming part thereof.

In the drawing, Fig. 1 is a perspective view of the lamp showing one side only of a picture frame base, the frame being adapted to expose a picture; Fig. 2 is a plan view of the lamp.

I claim:

The ornamental design for a lamp as shown and described.

JOSEPH SCHRADER.
